UNITED STATES PATENT OFFICE.

VICTOR R. HEFTLER, OF DETROIT, MICHIGAN, ASSIGNOR TO SOCIÉTÉ DU CARBURATEUR ZENITH, OF LYON, FRANCE, A CORPORATION OF FRANCE.

CARBURETOR.

Application filed June 25, 1918. Serial No. 241,851.

To all whom it may concern:

Be it known that I, VICTOR R. HEFTLER, a citizen of the United States, residing at Detroit, in the county of Wayne and State 5 of Michigan, have invented a new and useful Improvement in Carburetors, of which the following is a full, clear, and exact description, reference being had to the accompanying drawings, forming part of this 10 specification, in which—

Figure 1 is a side elevation of one form of my improved carburetor.

Figure 2 is a plan view thereof.

Figure 3 is a sectional view on the line 15 III—III of Figure 2, and

Figure 4 is a detail sectional view on the line IV—IV of Figure 3.

This invention relates to an improvement 20 in carburetors and is designed to provide an efficient device which can be readily and inexpensively manufactured.

One of the objects of my invention is to so arrange the oil feeds that I am enabled 25 to overcome all joints and plug openings between the inlets to the fluid feeds from the constant level chamber and the outlets therefrom. I accomplish this by forming the oil feed openings in the body of a main casting, and form the atmospheric well and 30 the emulsion chamber within a stem which extends from the main casting and which is surrounded by the bowl which forms the float chamber. Another object of my invention is to so form the emulsion passages 35 within the main casting that I am enabled to give a substantially straight main air passage from the air inlet to the intake pipe for the engine. Another object of my invention is to so place the stem, in which the 40 atmospheric well is formed, as well as the main jet and the emulsion conduit, that the feeds thereof are substantially at the center of the float chamber, which enables me to keep the gravity head for the jets when the 45 device is in an inclined position, very near the value of said jets when the carburetor is in its normal position. A still further object of my invention is to provide an air adjusting device for the slow-speed jet, 50 which is so arranged that adjustments can be made while the engine is running.

The precise nature of my invention will be best understood by reference to the accompanying drawings, which will now be 55 described, it being premised, however, that

various changes may be made in the details of construction and the general arrangement of the parts without departing from the spirit and scope of my invention as defined in the appended claims. 60

In the accompanying drawings, the reference character 2 designates the main or body casting, which is provided with a stem 3. This stem 3 has a vertical opening 4 therein which forms the atmospheric well, as well as an opening 5 adjacent thereto and parallel therewith, which forms the emulsion conduit, or conduit in which the minute globules of fuel are held in suspension during the operation of the carburetor to provide a combustible mixture. It is this mixture of fuel and air which is referred to as an "emulsion". The lower face of this casting 2 is provided with an annular seat surrounding the stem 3 for a bowl 6 which forms a float chamber 7. This bowl may be formed of a stamping or spun up from sheet metal, and is held in position by means of a spring 8 secured to the top of the casting and provided with fingers 9 which engage notched ears 10 connected to the rim of the bowl. The notches are formed with depressions for the reception of the ends of the fingers to lock the bowl in position on the casting. The casting 2 is provided with an inlet opening 11 for the reception of the fluid feed pipe. The outlet therefrom leading into the float chamber is controlled by means of a valve 12, which is adapted to close a port 13. 70 This valve 12 is slidably mounted in a sleeve 14, which has a threaded engagement with an opening in the casting, the port 13 extending through the sleeve 14, and communicating with the opening in which the valve is seated. Extending downwardly from the casting 2 and within the float chamber 7 are lugs 15, to which is pivotally connected a float 16. 75 17 is a lever extending from the pivotal connection of the float which engages the valve and is arranged to move it to its closed position when the float has been elevated to the proper point or permit said valve to open when the fluid in the float chamber passes below a predetermined level. 80

The upper face of the body casting 2 is machined, and secured thereto by screws 18 is a casting 19, the upper end of which is arranged to be secured to the end of the intake 85 110

pipe leading to the engine. This casting is provided with a through opening 20 which forms the mixing chamber, and mounted therein is a primary venturi 21. 22 is the usual throttle valve rotatably mounted within the mixing chamber. 23 is the air intake pipe which is secured to an annular seat on the casting 2, and rotatably mounted therein is a shutter valve arranged to be actuated by the lever 24. The main casting 2 is provided with a spider within the air chamber which forms a support for a boss 25 having an annular opening therethrough for the reception of the small or secondary venturi 26. 27 is an annular chamber within the boss 25 and surrounding the secondary venturi, which is in communication with the secondary venturi by means of a plurality of small radial openings 28. This annular chamber 27 is also in communication with the emulsion conduit 5 by means of a conduit 29. The conduit 29 is formed by drilling through the wall of the support 25, and then plugging the opening in the support 25, as shown in Figure 3. 30 is the main jet within the emulsion chamber 5, which has a screw-threaded engagement with the walls of the emulsion chamber, the lower end thereof being provided with a calibrated opening 31 for feeding gasoline to the main jet. 32 is a plug having a calibrated opening therethrough, and which is mounted in the stem 3, the calibrated opening being arranged to feed gasoline from the float chamber to the atmospheric well, and 33 is an opening extending from the atmospheric well into the emulsion chamber 5. 34 is an air opening leading from the atmospheric well into the float chamber.

40 The casting 19 is provided with an outwardly and downwardly extending arm 35 having a vertical opening therein and a transverse opening 36 communicating therewith and with the mixing chamber, to form a slow-speed jet. The vertical opening in the arm 35 is screw-threaded, as indicated at 37 for the reception of a threaded plug 38. The upper end of this plug is tapered and is arranged to form a valve adapted to be moved toward and from a conical seat 39 in the vertical opening. 40 is an air opening through the wall of the arm 35 for admitting air to the vertical opening below the seat 39. This plug is also provided with a tube 41 which extends a point adjacent to the lower end of the atmospheric well 4, while the upper end of this plug is provided with an opening, through which the gasoline passes to the slow-speed jet 36. Rotatably mounted in a cut-away portion of the arm 35 above a brace 42 is a bushing or collar 43. This bushing 43 is provided with internal serrations which engage corresponding projections on the plug 38, as clearly shown in

Figure 4, the arrangement being such that when the collar 43 is rotated, the plug member 38 will be moved toward or from the seat 39 to adjust the air feed to the slow-speed jet 36. The periphery of this sleeve is also provided with serrations which are engaged by a spring-pressed plunger 43^a, for locking the bushing 43 and the plug 38 in their adjusted positions. The lower end of the arm 35 is provided with a plurality of openings 44, through which air is admitted to the atmospheric well, and which openings are covered by means of a cylindrical screen 45 to filter the air passing to the atmospheric well.

The advantages of my invention result from the provision of a carburetor having a main or body casting, which contains all of the gasoline feed openings. Furthermore, from the provision of a stem having an atmospheric well therein as well as the emulsion chamber and main jet, and which stem extends from the main casting into the bowl forming the constant level chamber. Furthermore, from the provision of a structure in which the bowl forming the constant level chamber surrounds the stem and is removably secured to the casting. By this arrangement, the bowl can readily be removed from the main casting and all of the gasoline drained into the bowl, and afterwards any adjustment or removal of the calibrated opening nuts can readily be accomplished without removing various plugs to gain access thereto. A still further advantage results from the provision of a carburetor in which the main air passage is substantially in a straight line. Also from the provision of means for readily adjusting the air feed to the slow speed jet during the running of the engine.

I claim:

In a carburetor, a main body section, a float chamber secured against a lower surface of such body section, a gasoline inlet leading downwardly through the body section to the float chamber, a projecting portion on said main section having a channel therein for delivering fuel to a fuel outlet, a stem projecting downwardly from said main section having a fuel well formed therein, a secondary body section fitting against said main section and having a mixing chamber formed therein, a fuel feeding tube extending into the aforementioned well, and a projecting member extending from said secondary body section, said member constituting a supporting means for said fuel feeding tube and having a fuel passage formed therein for cooperating with said fuel feeding tube.

In testimony whereof, I have hereunto set my hand.

VICTOR R. HEFTLER.
